UNITED STATES PATENT OFFICE.

FRANK R. FIELD, OF GREENFIELD, MASSACHUSETTS.

ELECTRIC CLOCK.

SPECIFICATION forming part of Letters Patent No. 324,824, dated August 25, 1885.

Application filed June 1, 1885 (No model.)

To all whom it may concern:

Be it known that I, FRANK R. FIELD, of Greenfield, Franklin county, State of Massachusetts, have invented an Improvement in Electric Clocks, of which the following description, in connection with the accompanying drawings, is a specification, like letters on the drawings representing like parts.

My invention relates to an electric clock of that class in which an electro-magnet is employed to store power that is applied to a time-measuring pendulum, so as to maintain the oscillation of the pendulum, which in turn controls the circuit of the electro-magnet, changing its condition at each beat of the pendulum, so that the power of the said magnet may also be employed to turn the hands of the clock, or, in other words, count or indicate the number of beats of the pendulum, and the clock may also, through a suitable electric circuit, control other secondary clocks, maintaining them in unison with the main or primary clock.

The invention consists, mainly, in novel details of construction and arrangement of the electro-magnet and pendulum, and intermediate mechanism by which the one controls or affects the operation of the other. As shown, in this instance two electro-magnets are employed, being called into action alternately at the too-and-fro vibrations of the pendulum, and the said magnets are preferably of the kind known as "differential magnets," having two separate coils so related to one another that when the current is passing through both coils the effect on the core of the magnet is neutralized, but when the current passes through one only of the said coils the cores are magnetized, and the magnet produces its maximum attractive effect. This kind of magnet is preferred, as it diminishes or annuls the sparks that would otherwise be produced at the circuit closer and breaker controlled by the pendulum. The two magnets act alternatively to vibrate a single armature-lever in opposite directions on its pivot, and the said armature-lever is provided with a fork or two projections, which receive between them the free end of a spring connected with the pendulum-rod. The said spring and the projections of the fork constitute part of the circuit

of the magnets, and are so arranged that when the pendulum arrives near the end of its oscillation in one direction it reverses the actuating-current from one to the other of the said magnets in such manner that the armature-lever and fork are tilted so as to press against and strain the spring, bringing its elastic force into action to move or impel the pendulum in the other direction, at the end of which movement the condition is reversed and a similar impulse produced in the opposite direction, this impulse being sufficient to overcome the usual resistance to the movement of the pendulum, and thus maintain it steadily in vibration. The impulse on the pendulum does not depend upon the force exerted by the magnet on the armature-lever, which is always greater than required to strain the impelling-spring, which thus transmits a definite amount of the said force only derived from its own elasticity to the pendulum at each movement. The armature-lever also actuates the hands of the clock, advancing them a definite amount at each movement, so that the movement of the hands depends upon the time-measuring pendulum, as in other clocks.

Figure 1 is an elevation of the clock mechanism as seen looking toward the dial, the frame-work and hands of the clock being removed and the circuits being shown in diagram; Fig. 2, a side elevation of the clock mechanism, and Fig. 3 a rear elevation of the actuating mechanism of the secondary clock, the circuit-connection between which and the main or primary clock shown in Fig. 2 being indicated in diagram.

The main clock contains a pendulum-bob, *a*, (see Fig. 1,) supported on a rod, *a'*, adapted to oscillate about a point of support in any usual manner, being, as shown in this instance, hung upon a slender spring, *a''*.

The pendulum and its rod may be constructed in any approved manner to compensate for changes in temperature, so that its oscillations form as nearly as possible an accurate measure of time.

The impulses which make up for the natural resistance to the movement of the pendulum are derived from the elastic force of an impelling-spring, *b*, fixed at *b'* upon the pendulum-rod and tending to assume a position par-

allel with the axis of the rod. The free end of the spring or a projection, b^2 , therefrom enters between two projections, c c' , on an armature-lever, d , pivoted to oscillate in a plane parallel with the plane of oscillation of the pendulum-rod a' , and provided with an armature, d' , between the opposite poles of two electro-magnets, e e' . If at the end of a vibration of the pendulum in one direction the armature-lever d is moved so as to carry the projections c c' in the opposite direction, as shown in Fig. 1, the spring b will be strained, and will tend to move the pendulum in the opposite direction to that in which it was last moving, and will thus provide the necessary impulse to keep up the movement of the pendulum. In order to thus move or tilt the armature-lever d at the end of each vibration of the pendulum to thus strain the spring b for the next impulse, the circuit of the magnets e e' is controlled by the movements of the pendulum, and the cores of one magnet are magnetized and of the other demagnetized at or near the end of each vibration of the pendulum. As shown, in this instance each magnet e e' has two coils, which will for distinction be called the "first" and "second." The first coil is in a permanently-closed circuit, 2 3 4 5, for the magnet e' , and 2 3 6 7 5 for the magnet e with the battery B. One terminal of each of the second coils is connected by wires 8 and 9, respectively, with one pole of the battery B, and the other terminal of the second coil is connected, by wire 10 for the magnet e and wire 12 for the magnet e' , with the projections c c' , respectively, which are insulated from one another, and the other pole of the battery is connected by wire 13 with the pendulum-rod and spring b' , so that when the said spring b' or its projection b^2 touches one or the other of the projections c or c' the circuit is completed through both coils of the corresponding magnet, e or e' , and at the same time the spring b is disconnected from the opposite projection, so that only one coil is in circuit in the other magnet, which is consequently energized and attracts the armature d' with maximum effect.

The parts are represented in Fig. 1 in the position assumed just after the pendulum in its movement toward the left, as seen in the said figure, has brought the spring b into contact with the projection c , thus completing the circuit 2 13 b c 10 9 5 through the second coil 55 of the magnet e , so that the current passes through both coils of the said magnet, thus demagnetizing it, and just before the projection b^2 had thus come into contact with the projection c it left the projection c' , thus 60 breaking the circuit through the second coil of the magnet e' , leaving the said magnet energized by the continuous current in its first coil, so that as soon as the magnet e was demagnetized, as just described, the unopposed 65 attraction of the magnet e' on the armature d' moved the latter in the direction to press the

projection c against the spring b , straining the latter, as shown, so that its elastic force in the effort to straighten or assume its normal condition acts upon the pendulum, impelling it 70 toward the right. This impulse will continue during the movement of the pendulum until, finally, the spring will cease to bear on the projection c , and then in the farther movement of the pendulum, due to its momentum, 75 the spring b will become separated from the projection c , breaking the circuit of the second coil of the magnet e , so that for a moment both magnets will be energized; but no movement will take place in the armature, as it is 80 nearer the poles of the magnet e' by which it was last attracted than to those of the magnet e ; but immediately after, in the farther movement of the pendulum, the projection b^2 will touch the projection c' , thus completing the 85 circuit in the second coil of the magnet e' , thereby demagnetizing the said magnet and leaving the attractive force of the magnet e unbalanced, so that the armature d' will be moved toward it again straining the spring 90 b , as before described, but in the opposite direction, and the operations described will continue indefinitely as long as the battery supplies a current. The movements of the armature-lever d may also be used to turn the 95 hands of the clock or indicate the time measured by the pendulum in any usual manner. As shown, the armature-lever is provided with an anchor, d'' , having pallets d''' , which alternately engage the teeth of a wheel, f , shown 100 as provided with thirty teeth and moving the space of half a tooth at each vibration of the pendulum and consequent vibration of the armature-lever, so that if the pendulum is of proper length to beat seconds the wheel f will 105 turn once in a minute, and a hand or pointer, f' , (see Fig. 2,) on the arbor f'' of said wheel will thus constitute a seconds-hand for the clock. The arbor f'' of the wheel f may actuate, through suitable speed-reducing wheel-work, g , a minute-hand, g' , which will make one complete revolution in an hour, and by additional wheel-work g'' the hour-hand g''' may be made to revolve once in twelve hours, the three hands being shown in this instance as 115 concentric with one another, although it is obvious that, if desired, the seconds-hand might turn around a different axis from the other hands.

In order to actuate any number of clocks at 120 different places in unison with the main clock thus far described, the wheel f may be made to control an electric circuit extending to the additional or secondary clocks, the mechanism of one of which is shown in Fig. 3, and consists, 125 essentially, of an electro-magnet, m , in the circuit 20 21, including a battery, B' , and a circuit-closer controlled by the main clock. The said circuit-closer consists of two springs, n , normally insulated from one another, and a 130 pin, n' , projecting from the wheel f , so that at one moment in the revolution of the said wheel

the pin will touch both springs and complete the circuit connected with them, thus energizing the magnets m of as many secondary clocks as may be included in the circuit 20 5 21. The armature m' of the magnet m is then attracted, and its lever m^2 is provided with a pawl, o , which is then moved over one tooth of the wheel p , which has sixty teeth, and when the magnet m is subsequently demagnetized in the movement of the wheel f , which disconnects the pin n from the springs n' , the retractor m^3 will withdraw the armature m' from the magnet, and in this movement the pawl o will turn the wheel p for the space of one tooth. The said pawl o is provided with an arm, o' , about at right angles to its line of action on the wheel p , and the movement of the said pawl under the action of the retractor is limited by a stop, o^2 , engaging the said arm o' , and thus limiting its movement, and at the same time forcing the end of the pawl in between the teeth of the wheel p , thus positively locking the latter and preventing it from overthrowing or moving by its momentum beyond the point to which it is positively moved by the pawl. The retaining-pawl r prevents backward rotation of the wheel p when the actuating-pawl o is moved up to engage another tooth, and this latter movement of the pawl o is limited by a stop, m^4 , for the armature-lever m^2 , so that the said pawl o can move over only one tooth at a time, and the chance of a false movement of the wheel p is reduced to a minimum. 35 The arbor of the wheel p may be provided with a hand which will revolve once in an hour, and thus indicate, in connection with a suitable dial, the time to the nearest minute as measured by the main or primary clock, 40 and the usual speed-reducing wheel-work will be employed to actuate an hour-hand for the said dial.

It is obvious that instead of using two electro-magnets, $e e'$, in the main clock, a single magnet and retractor might be used; and instead of differential magnets ordinary magnets having a single coil might be used, the differential magnets being employed in order to prevent sparks at the circuit closer controlled by the pendulum. 45 50

I claim—

1. The combination of a pendulum with an impelling-spring fixed at one end upon the pendulum-rod, and an electro-magnet, armature, and armature-lever which engages and strains the said spring, the spring forming a part of the circuit of the magnet and controlling its operation, substantially as described. 55

2. The pendulum and impelling device co-operating therewith, combined with an electro-magnet having two coils, one of which is in a permanently-closed circuit, and the other of which is in a circuit controlled by the pendulum, and an armature for the said magnet, 60 co-operating with the pendulum-impelling device, substantially as and for the purpose set forth. 65

3. The pendulum and impelling-spring connected therewith, combined with two electro-magnets, and an armature and armature-lever therefor provided with two insulated projections, which co-operate with the impelling-spring, straining the said spring to impart an impulse to the pendulum, and controlling, in connection with the spring, the circuit 70 75 of the magnets, substantially as described.

In testimony whereof I have signed my name to this specification in the presence of two subscribing witnesses.
